UNITED STATES PATENT OFFICE.

OLAF LARSEN, OF FORT ATKINSON, WISCONSIN, ASSIGNOR TO THE CREAMERY PACKAGE MFG. COMPANY, OF CHICAGO, ILLINOIS, A CORPORATION OF ILLINOIS.

DELIVERY MECHANISM FOR CAN WASHERS.

Application filed October 19, 1927. Serial No. 227,072.

The invention relates to mechanism for delivering cans from can washing machines after the cans have been submitted to cleansing treatment, and is more particularly related to such mechanism adapted to milk can washing machines of the type disclosed in U. S. Patent No. 1,604,505, granted October 26th, 1926, to Valerius & Larsen.

In machines of such type the milk cans are moved in inverted position progressively through a series of washing and drying stations, the can covers being similarly treated while travelling a separate path through the machine. At the end of those operations the cans are delivered in upright position to a suitable conveyor or receiving table, and the covers placed upon the cans.

The principal object of this invention is to provide automatic mechanism for assembling the covers with the cans, inverting the cans into upright position, and discharging them from the machine, with a minimum of wear and the prevention of damage to the cans.

Other objects and advantages will be apparent in the following detailed description of a preferred embodiment of the invention which has been selected for illustration in the accompanying drawings. It will be understood, however, that various changes in form, construction and arrangement may be made by those skilled in the art without departing from the spirit and scope of the invention as expressed in the appended claims.

In the drawings:

Figure 1 represents an end view in elevation of the can delivery mechanism as applied to a washing machine similar to that illustrated and described in the above mentioned Patent No. 1,604,505.

Fig. 2 is a side elevation of the delivery mechanism and a fractional portion of the washing machine with which it is associated.

Fig. 3 is a view in elevation of the opposite side of the mechanism and fractional portion of the machine.

Fig. 4 is a plan view and Fig. 5 is a fractional sectional elevation illustrating a portion of the can forwarding mechanism.

Referring to the drawings the numeral 1 indicates the main body portion of the can washing machine within which are housed devices for effecting the cleansing of a series of cans moving progressively through the

machine. The washing means, forming no part of the present invention, is not further described herein.

As fully set forth in the aforesaid patent and illustrated in part only herein, the cans are moved through the washing machine in an inclined inverted position, the cans resting with their mouths supported upon a plurality of rails 2 extending through the machine. The body portions of the cans are further supported by a laterally positioned rail 3 suitably mounted on the frame structure of the main body of the machine.

An intermittently progressive forward movement of the cans is effected by means of a pair of parallel reciprocating bars 4 and 5 having longitudinal sliding support on brackets, of which one is indicated at 6. The bar 5 moves longitudinally on a fixed axis while its complementary bar 4 is moved both longitudinally and laterally to effect contact with the cans during the forward movement of the bar, the cans being engaged between pairs of spaced toothed members 7 mounted on the bar 4.

As fully set forth in the afore-mentioned patent, power is applied to the bar 4 to effect a longitudinally reciprocatory movement, the bar 4 being connected by means of a plurality of pivot links, of which one is indicated at 8, with the other bar 5 which is confined in its movement to a longitudinal reciprocatory travel on a fixed axis. The consequence of the relation of the two bars is that in its forward movement the teeth 7 engage a can and move it forwardly through the length of advance of the bar 4. Upon reversal of the movement of the bar 4, the links 8 withdraw the teeth 7 from engagement with the can, leaving the latter in its advanced position while the bar 4 is withdrawn to the rearward limit of its longitudinal movement through a path represented in broken lines at 9.

As further fully set forth in the afore-mentioned patent, the covers for the several cans are conveyed through the machine by means of an intermittently operating belt conveyor, a portion of which is illustrated at 10. The movement of the conveyor 10 is arranged to advance the covers in time with the cans, so that each can and its cover reaches the outer end of the combined conveying mechanisms at the same time.

The cover conveyor 10 is intermittently

operated by the bar 5 through a dog 11 (Fig. 3) mounted thereon and engaging a chain belt 12 driving a shaft 13 oppositely driving a belt 14 connected to the shaft 15, the latter carrying a suitable pulley or sprocket in driving engagement with the conveyor 10.

As further described and illustrated in the afore-mentioned patent, the machine is provided with a can receiving shelf or platform 16 upon which the cans are inverted into upright position after leaving the supporting rails and advancing bar of the machine conveyor. The platform 16 is preferably provided with lateral walls 17 about two sides thereof, the walls carrying a resilient buffer member 18 to receive the shock of the falling can. It is preferable also that the shelf 16 be mounted with a resilient under-support as indicated at 19 also adapted to break the jar of the falling can.

Adjacent the open side of the platform 16 is mounted a conventional roller conveyor 20 over which the cans may be advanced for disposal after their treatment in the washing machine. The cans are preferably started over the conveyor 20 by means of a pusher plate 21 which operates during the return stroke of the can advancing bars to push the can last dropped upon the platform 16 outward upon the conveyor 20, whereupon its further movement is preferably accomplished by gravity.

The pusher plate 21 may be actuated by means of a reciprocating bar 22 upon which the plate is mounted, the bar extending through the side wall about the platform and being operatively supported between two spaced pairs of rollers 23 and 24 mounted on suitable brackets secured to the frame structure of the machine. The bar 22 is provided with a bracket 25 upon which is pivoted a link 26 having pivotal connection at its opposite end with a crank arm 27 rigidly mounted on a shaft 28 having suitable bearings supported on the frame structure of the machine.

The shaft 28 is provided with a rocking pitman 29 actuated through a link connection 30 with a second pitman 31 carried on a shaft 32 having its bearings on the upper structure of the machine, the pitman 31 being actuated by a driving rod 33 receiving power from any suitable mechanical source, preferably as fully described and illustrated in the afore-mentioned patent.

The invention forming the subject matter of this application comprises means for receiving the cans from the ends of the guide rails and advancing bar provided in the machine, and for receiving also the advancing covers from the end of their conveyor, for placing the cover in the can mouth, and for inverting the can and placing it in upright position upon the platform 16.

The mechanism for accomplishing these

results is mainly supported upon a bracket 34 mounted on the end structure of the washing machine and provided with bearings for a rock shaft 35 extending endwardly from the machine. Associated with the rock shaft 35 is a can receiving and inverting chute 36 comprising a trough like structure of substantially semi-cylindrical form secured to a cradle 37 which is fixed upon the rock shaft 35. The semi-cylindrical side 75 wall of the chute 36 is provided with an end wall 38 at its lower end when in normal position, the upper end being open. Adjacent the lower end wall and within the chute is a filler member 39 having a curved recess in 80 its upper surface substantially concentric with the semi-cylindrical wall of the chute.

In normal position the chute 36 is adapted to receive, with the forward movement of the can and cover advancing conveyors of 85 the washing machine, first, a cover which rolls down the inclined endward portion of the cover conveyor indicated at 40 in Fig. 2 and drops into the recessed upper surface of the filler element 39 coming to rest 90 against the end wall of the chute. Next, a can is dropped into the chute from the end of the guide rails of the machine and slides downward upon the cover, the latter being supported in position to enter the mouth of 95 the can as the latter slides toward the end wall of the chute.

The discharge of the can from the machine conveyor into the chute is facilitated by providing a series of rollers 41 mounted on 100 a common axis and supported at the extremity of the guide rails upon which the mouth of the can rests in its progress through the machine. Upon reaching the end of its travel on the guide rails the can 105 is thrown into the chute by means of a lever 42 pivoted on a suitable bracket 43 secured upon the extreme end of the advancing bar 4, and engaging the side of the body of the can in the last stage of its forward movement on the machine guide rails.

The lever 42 is retained in normal position by means of a spring 44 having its ends secured respectively to the lever and the bar 4, the lever in normal position functioning 115 similarly to the can advancing teeth 7 previously described. As the forwarding bar 4 approaches the forward limit of its movement an oppositely extending lug 45 carried by the lever 42 is engaged by a rigidly supported stop member 46 preferably comprising a bolt adjustably mounted in a bracket 47 rigidly secured to the frame structure of the machine. Engagement by the lug 45 with the stop member 46 causes a 120 sharp forward movement of the lever 42 in contact with the body of the can, and effects the pushing of the can from the end of the guide rails with sufficient force to carry it 125 into the receiving chute 36.

During the return movement of the bar 4, the lever 42 is withdrawn laterally from contact with the next succeeding can until the forwarding bar reaches the return limit 5 of its movement, when the further advance of the bar effects the similar pushing of the next can into the chute.

During the reverse movement of the advancing bar 4, the chute 36 is rotated about the axis of the shaft 35 into position as indicated by the dotted lines in Fig. 1, which causes the can, with its cover placed therein, to slide from the open end of the chute now lowermost and be deposited in upright position upon the platform 16, from which the can is pushed out upon the gravity conveyor as previously described.

The rotation or rocking movement of the chute 36 is effected by means of a crank 48 fixed on the shaft 35, the free end of the crank being pivoted to a connecting link 49, the opposite end of the link being pivoted intermediately upon a lever 50 having a stationary fulcrum upon a bearing pin 51 mounted in a bracket 52 secured to the end structure of the machine.

The opposite end of the lever 50 is pivotally connected by means of a link 53 with one end of the pitman 29. The actuating mechanism for the pitman 29, operatively connected as previously described herein, is arranged in synchronism with the longitudinal movement of the advancing bar 4, as fully set forth in the afore-mentioned patent, with the effect in the present arrangement that the inverting chute 36 is lowered into position to receive the cans and covers from the machine conveyors as the latter are operated forwardly, and to be rotated by the shaft 35 during the reverse movement of the advancing bar to deposit the can and cover upon the platform 16.

The provision of this mechanism avoids the common expedient of permitting the can to fall from the end of the guide rails, striking a fulcrum obstacle which effects the inversion of the can in its fall toward the platform 16. The interposition of the chute 36 accomplishes the comparatively gentle handling of the can whereby wear and denting of the sides of the can is avoided, and at the same time the placing of the cover in the can mouth is automatically effected.

In the event that a can may become accidentally out of position in the chute, or the preceding can failed to have cleared from the platform 16, damage to the can and inverting chute mechanism is avoided by the provision of a friction clutch connection between the rock shaft 35 and the cradle 37 which carries the chute. This clutch connection preferably comprises an annular support 54 rigidly associated with the cradle 37 and upon which is securely mounted an annular friction disk 55 having a central aper-

ture. Inwardly of the annular supporting ring 54 is provided a friction plate 56 rigidly mounted on the shaft 35 and engaging the inner marginal face of the friction disk.

Outwardly and oppositely of the friction plate 56 is a second friction plate 57 mounted on the shaft 35 and bearing upon the outer marginal surface of the friction disk 55. A plurality of bolts 58 having screw threaded adjustable mounting in the inner plate 56 extend freely through openings in the outer plate 57, between which latter and the heads of the bolts are confined compression springs 59 which effect the pressure of the two plates 56 and 57 upon the friction disk. If for any reason the chute 36 is obstructed against rotative movement, the clutch members last described will slip in their engagement and avoid damage to the mechanism.

It will here be apparent that I have provided an efficient automatic mechanism of simple construction whereby the covers are automatically placed in their respective cans and the latter inverted without damage into upright position upon the receiving platform.

I claim as my invention:

1. In combination with means for forwarding an inverted container and a cover therefor in separated relation, a chute adjacent the end of said forwarding means normally disposed in inclined position to receive and retain said cover and said container and cause said container to slide into engaging relation with said cover, and a support for said chute operable to swing said chute into reversely inclined position for the release of said container and its engaging cover therefrom in upright position.

2. The combination of a conveyor having a reciprocatory member adapted to forward a container by successive advancing movements along said conveyor, a lever intermediately pivoted on said reciprocatory member having one end positioned to engage a container approaching the end of said conveyor, and a stationary abutment positioned for engagement by the other end of said lever in the forward movement of said reciprocatory member whereby said lever is actuated to push said container outwardly from the end of said conveyor.

3. The combination of a conveyor having a reciprocatory member adapted to forward an inverted container by successive advancing movements along said conveyor, a lever intermediately pivoted on said reciprocatory member having one end positioned to engage a container approaching the end of said conveyor, a stationary abutment positioned for engagement by the other end of said lever in the forward movement of said reciprocatory member whereby said lever is actuated to push said container outwardly from the end of said conveyor, and means for

receiving said container operable to swing said container endwardly and discharge the same in upright position.

4. The combination of a conveyor operable to effect the progressively forward movement of a container positioned thereupon and to discharge the same at the end thereof, and a second conveyor operable to move a container cover uniformly with said container, 10 said second conveyor being endwardly adapted to effect the discharge of said cover therefrom in advance of the discharge of said container.

5. The combination of a conveyor operable to effect the progressively forward movement of a container positioned thereupon and to discharge the same at the end thereof, and a second conveyor operable to move a container cover uniformly with said container, 15 said second conveyor having an inclined end portion adapted to permit the sliding of said cover thereover with accelerated speed effective to discharge said cover therefrom in advance of the discharge of said container.

6. The combination of a conveyor operable to effect the progressively forward movement of an inverted container positioned thereupon and to discharge the same at the 20 end thereof, a second conveyor operable to move a container cover uniformly with said container, said second conveyor having an inclined end portion adapted to permit the sliding of said cover thereover with accelerated speed effective to discharge said cover therefrom in advance of the discharge of said container, and a chute adjacent the ends of said conveyors, said chute being normally disposed in inclined position and having its 25 lower end portion adapted to receive and retain said cover, the upper portion of said chute being adapted to receive said container to slide thereupon into engaging relation with said cover.

45 7. The combination of a conveyor operable to effect the progressively forward movement of an inverted container positioned thereupon and to discharge the same at the end thereof, a second conveyor operable to move a container cover uniformly with said container, said second conveyor having an inclined end portion adapted to permit the sliding of said cover thereover with accelerated speed effective to discharge said cover therefrom in advance of the discharge of said container, a chute adjacent the ends of said conveyor, said chute being normally disposed in inclined position and having its lower end portion adapted to receive and 50 retain said cover, the upper portion of said chute being adapted to receive said container and permit said container to slide thereupon into engaging relation with said cover, and a support for said chute operable to swing said chute into reversely inclined position to

discharge said container and cover therefrom in upright position.

8. In combination with a pair of conveyors respectively adapted to forward an inverted container and a cover therefor and to discharge the same from the ends thereof, 70 an inclined chute positioned to receive said container and said cover from said conveyors in separated relation, and means at the lower end of said chute to position said cover in register with the mouth of said container, the inclination of said chute causing said container to slide thereupon into engaging relation with said cover.

9. In combination with a pair of conveyors respectively adapted to forward an inverted container and a cover therefor and to discharge the same from the ends thereof, 80 an inclined chute positioned to receive said container and said cover from said conveyors in separated relation, means at the lower end of said chute to position said cover in register with the mouth of said container, the inclination of said chute causing said container to slide thereupon into engaging 85 relation with said cover, and means for reversing the inclination of said chute to discharge said container therefrom in upright position.

10. The combination of an inclined chute 90 adapted to receive a container and a cover therefor in separated relation, said chute having a lower end abutment for the retention of said cover, and a cover positioning member adjacent said abutment effective to 100 support said cover in register with the mouth of said container, the inclination of said chute causing said container to slide into engagement with said cover.

11. The combination of a chute adapted to 105 receive a container in inverted position, a rotatable support for said chute operable to swing said chute into reverse position for the discharge of said container therefrom in upright position, a driven rock shaft, and a 110 clutch connection between said rock shaft and said support effective to permit the stoppage of said chute during the movement of said rock shaft.

12. The combination of a conveyor having 115 a reciprocatory member adapted to forward a series of containers along said conveyor and to discharge said containers successively therefrom, a chute adjacent said conveyor normally disposed in inclined position to receive and retain said container, a support for said chute operable to swing said chute into reversely inclined position for the release of said container in upright position, and operable connecting means between said reciprocatory member and said support effective to move said chute into normal position during the forwarding movement of said member.

13. The combination of a conveyor having 120

ing means for forwarding a container there-
upon and for discharging said container
from the end thereof, a chute adjacent said
conveyor normally disposed in inclined posi-
5 tion to receive and retain said container, said
chute being swingable into reversely inclined
position to discharge said container there-

from in upright position, and a platform po-
sitioned to receive said container when dis-
charged from said chute.

10 In testimony whereof, I have hereunto
affixed my signature.

OLAF LARSEN.
